CLAIM

The ornamental design for an identification badge, as shown and described.

DESCRIPTION

FIG. 1 is a perspective view of an identification badge showing our new design;

FIG. 2 is a front plan view thereof;

FIG. 3 is a rear plan view thereof;

FIG. 4 is a right side elevational view thereof;

FIG. 5 is a left side elevational view thereof;

FIG. 6 is a top elevational view thereof;

FIG. 7 is a bottom elevational view thereof;

FIG. 8 is a perspective view of an identification badge showing a second embodiment of our new design;

FIG. 9 is a front plan view thereof;

FIG. 10 is a rear plan view thereof;

FIG. 11 is a right side elevational view thereof;

FIG. 12 is a left side elevational view thereof;

FIG. 13 is a top elevational view thereof; and,

FIG. 14 is a bottom elevational view thereof.

Stippling is used in FIGS. 1-13. The stippling shown represent surfaces of the article having a contrast in color with respect to surfaces of the article that do not include the stippling.

The broken lines shown represent portions of the article that form no part of the claimed design.

1 Claim, 2 Drawing Sheets
